UNITED STATES PATENT OFFICE.

FRANK E. LITCHFIELD, OF MONTGOMERY, ALABAMA, ASSIGNOR TO THE GEORGIA SHOW CASE COMPANY, OF MONTGOMERY, ALABAMA, A CORPORATION OF GEORGIA.

DESIGN FOR A PILASTER.

Application filed May 14, 1923. Serial No. 6,152. Term of patent 14 years.

To all whom it may concern:

Be it known that I, FRANK E. LITCHFIELD, a citizen of the United States, residing at Montgomery, in the county of Montgomery and State of Alabama, have invented a new, original, and ornamental Design for Pilasters, of which the following is a specification, reference being had to the accompanying drawing, forming part thereof.

Figure 1 is a front or face view of a pilaster showing my new design; and

Figure 2 is a side or edge view of the same.

I claim:

The ornamental design for a pilaster, substantially as shown.

In witness whereof, I have hereunto set my hand at Montgomery, Alabama, this 9 day of May, 1923.

FRANK E. LITCHFIELD.
